(57) CLAIM

The ornamental design for a mail and key holder, as shown and described.

DESCRIPTION

FIG. 1 is a perspective view of a mail and key holder showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of the mail and key holder, but with a different panel insert.

The stippling on the panel insert of FIGS. 1-7 represents shading of a surface having contrast to the surface of the wire frame.

The broken lines shown in the figures represent portions of the mail and key holder that form no part of the claimed design.
